Patented Sept. 15, 1970

218,722

PLUMBER'S TOOL CARRIER OR SIMILAR ARTICLE

Joseph R. Vaccaro, Flanders, N.J. 07836

Filed Sept. 26, 1969, Ser. No. 19,304

Term of patent 14 years

Int. Cl. D3—99

U.S. Cl. D87—1

FIG. 1

FIG. 2

FIG. 3

FIG. 4

FIG. 5

FIG. 6

FIG. 1 is a front perspective view of a plumber's tool carrier or similar article showing my new design.

FIG. 2 is a front elevational view of the tool carrier.

FIG. 3 is an end elevational view, both ends having the same appearance.

FIG. 4 is a rear elevational view.

FIG. 5 is a top plan view.

FIG. 6 is a bottom plan view of my novel design.

I claim:

The ornamental design for a plumber's tool carrier or similar article, as shown and described.
